(57) **CLAIM**

I claim the ornamental design for a wine rack and shelf, as shown and described.

DESCRIPTION

FIG. 1 is a front right perspective view of a first embodiment of a wine rack and shelf showing my new design;

FIG. 2 is a front view thereof;
FIG. 3 is a rear view thereof;
FIG. 4 is a right side view thereof;
FIG. 5 is left side view thereof;
FIG. 6 is a top view thereof;
FIG. 7 is a bottom view thereof;
FIG. 8 is a front right perspective view thereof in a typical usage environment;
FIG. 9 is a front right perspective view thereof in an inverted usage position;
FIG. 10 is a front view thereof;
FIG. 11 is a rear view thereof;
FIG. 12 is a right side view thereof;
FIG. 13 is left side view thereof;
FIG. 14 is a top view thereof;
FIG. 15 is a bottom view thereof;
FIG. 16 is a front perspective view thereof in a typical usage environment;
FIG. 17 is a front right perspective view of a second embodiment of a wine rack and shelf;
FIG. 18 is a front view thereof;
FIG. 19 is a rear view thereof;
FIG. 20 is a right side view thereof;
FIG. 21 is left side view thereof;
FIG. 22 is a top view thereof;
FIG. 23 is a bottom view thereof;
FIG. 24 is a front right perspective view thereof in a typical usage environment;
FIG. 25 is a front right perspective view thereof in an inverted usage position;
FIG. 26 is a front view thereof;
FIG. 27 is a rear view thereof;
FIG. 28 is a right side view thereof;
FIG. 29 is left side view thereof;
FIG. 30 is a top view thereof;
FIG. 31 is a bottom view thereof; and,
FIG. 32 is a front perspective view thereof in a typical usage environment.

The features shown in broken lines form no part of the claimed design.

1 Claim, 16 Drawing Sheets
